FILLING REPLENISHING MECHANISM FOR LOOMS.

(Application filed Jan. 9, 1902.)

(No Model.)

2 Sheets—Sheet 2.

UNITED STATES PATENT OFFICE.

CHARLES F. ROPER, OF HOPE DALE, MASSACHUSETTS, ASSIGNOR TO DRAPER COMPANY, OF HOPE DALE, MASSACHUSETTS, A CORPORATION OF MAINE.

FILLING-REPLENISHING MECHANISM FOR LOOMS.

SPECIFICATION forming part of Letters Patent No. 711,736, dated October 21, 1902.

Application filed January 9, 1902. Serial No. 88,974. (No model.)

To all whom it may concern:

Be it known that I, CHARLES F. ROPER, a citizen of the United States, and a resident of Hopedale, county of Worcester, State of Massachusetts, have invented an Improvement in Filling-Replenishing Mechanism for Looms, of which the following description, in connection with the accompanying drawings, is a specification, like letters on the drawings representing like parts.

In United States Patent No. 659,628, dated October 9, 1900, a loom is shown provided with main and auxiliary filling forks or detectors to detect failure of filling on the picks in which failure occurs, one of the forks operating to arrest the take-up and effect stoppage of the loom upon detection of filling failure, while the other fork prevents operation of the take-up and obviates the formation of thin places in the cloth. Such apparatus was designed for use either in connection with automatic filling-replenishing mechanism or without such mechanism, in the former case such mechanism being controlled as to its operation by the main fork and in the latter case such fork operated to effect stoppage of the loom.

When using filling-replenishing mechanism of the "Northrop" type—such, for instance, as in United States Patent No. 529,940—the filling-thread extends from the feeder or hopper to the nearer edge of the cloth on the first shot of the shuttle after replenishing is effected and so remains for succeeding picks until severed, the automatic severance of such portion of filling being provided for by a temple-thread cutter adjacent the selvage of the cloth and by other means near the replenishing shuttle-box. It sometimes happens that the severance of such portion of filling is not promptly effected, and in actual practice from one to three or more picks intervene after filling-replenishing before this filling end is severed. With double-fork mechanism, such as shown in Patent No. 659,628, when used in connection with filling-replenishing mechanism a very practical difficulty presents itself by reason of this end of filling, for, remembering that the auxiliary fork is located at the replenishing side of the loom, the unsevered end of filling acts upon this fork and tilts

it upon each forward beat of the lay, whether the running filling be intact or broken. Thus it will be manifest that so long as such filling end is present the proper function of the auxiliary fork to detect failure of the running filling cannot be performed, and if such filling fails on the shot of the shuttle toward the replenishing side of the loom it will be undetected, there will be no arrest of the take-up nor let-back, and a thin place in the cloth will be formed.

My present invention has for its object the production of means for insuring the proper coöperation of the auxiliary fork with the running filling entirely irrespective of the presence or absence of the filling end between the cloth and the replenishing mechanism, so that the objectionable feature hereinbefore referred to is entirely obviated, and a double-fork mechanism will operate as successfully and accurately in connection with filling-replenishing mechanism as without it.

The various novel features of my invention will be hereinafter described, and particularly pointed out in the following claims.

Figure 1 is a top or plan view, centrally broken out, of a loom provided with filling-replenishing mechanism and having one embodiment of my present invention applied thereto. Fig. 2 is an enlarged transverse detail on the line 22, Fig. 1, and looking toward the left, of the auxiliary fork and the means whereby its proper operation is effected. Fig. 3 is a similar view, but showing the manner in which the auxiliary fork operates in order to prevent interference by the filling end. Fig. 4 is an enlarged plan view of the auxiliary fork; and Fig. 5 is a longitudinal section thereof on the line 55, Fig. 4, to more clearly illustrate the construction of the fork.

In the specification and following claims the term "filling end" will be frequently used, indicating the portion of filling laid on the pick immediately succeeding filling-replenishing and extending from the cloth to the feeder of the replenishing mechanism, and the term "running filling" will be employed to indicate the filling laid by the shuttle and not including the filling end.

Referring to Fig. 1, the lay A³, shuttle-boxes B B^X thereon, the automatically self-

threading shuttle S^x , and the breast-beam A^{40} , having at one end the notched holding-plate N for the shipper S and at the other end supporting the filling-replenishing mechanism, 5 of well-known structure and comprising a transerrer f' and a feeder F to contain a supply of filling-carriers b , may be and are all of well-known construction and operate in usual manner.

10 The loom is provided with suitable take-up mechanism—such, for instance, as in United States Patent No. 643,284, dated February 13, 1900, though I have herein shown only a sufficient portion of such mechanism to illustrate 15 the control thereof by or through the detection of filling failure, inasmuch as the take-up mechanism is not of my invention and the particular type thereof is not essential to this present invention.

20 The controlling rock-shaft d' , which governs the operation of the replenishing mechanism, is mounted in suitable bearings 20 on the loom-frame and has fast upon it the hub d^x of an upturned arm d , bent at its upper 25 end into the path of movement of the outer end of a slide f^x , movable in a guide f^2 , fast on the breast-beam, the slide having pivotally mounted thereupon at its inner end a filling fork or detector f of usual construction, the 30 tail of the detector co-operating with the weft-hammer W , Fig. 1, upon detection of filling failure when the shuttle is shot from right to left to effect outward movement of the slide and operatively rock the controlling rock-shaft d' .

35 A knock-off lever n^x on the breast-beam is so arranged that its inner end will be engaged by a dog f^8 on the slide f^x upon outward movement of the latter a predetermined 40 number of successive times to thereby release the shipper S and stop the loom, substantially as in United States Patent No. 529,943.

45 For convenience the filling-detector f will be termed the "main" filling-detector, and it will be seen that it is located at that side of the loom opposite the filling-replenishing mechanism and has a detecting action only on the pick on which the shuttle is shot from right to left.

50 A depending arm d^2 , fast on the rock-shaft d' , (see Figs. 2 and 3,) has a lateral lug d^3 to engage the upturned end a^{10} of the take-up pawl-carrier a' , the only member shown of the take-up mechanism, rotative movement of 55 said rock-shaft in the direction of the arrow 6, Figs. 2 and 3, disengaging the take-up pawl from the usual ratchet and arresting the take-up, as in Patent No. 643,284, and permitting let-back, if desired.

60 A tubular shaft c^x loosely surrounds the rock-shaft d' , between the hub d^x and the right-hand bearing 20, (see Fig. 1,) having secured upon it the hub of a depending short arm c' , provided with a lateral lug c^2 , extended across the outer edge of the arm d^2 , Figs. 2 and 3, so that when said tubular shaft is rocked in the direction of arrow 6 the oper-

ation of the take-up mechanism will be arrested through co-operation of arms $c' d^2$. The rocking of this tubular shaft is effected by or 70 through an auxiliary filling-detector upon detection of filling failure when the shuttle is shot from left to right, said auxiliary detector being located at the replenishing side of the loom and being peculiarly constructed 75 and operating in a novel manner, as will be described.

A stand g^2 , secured to the breast-beam at the replenishing side of the loom, has movably mounted therein a slide g^x , whose outer 80 end is adapted upon outward movement to engage the upper end c^3 of an upturned arm c^4 , having a clamp-hub c^5 , secured to the tubular shaft c^x , (see Figs. 2 and 3,) a spring s^x , attached to said arm, and the stand g^2 , serving to return the slide g^x to normal position after outward movement thereof.

When filling failure is detected by the auxiliary filling-detector, the slide g^x is moved outward by an auxiliary weft-hammer W^x , 90 Figs. 1, 2, 3, and 5, to rock the tubular shaft c^x and arrest the operation of the take-up mechanism, as described.

Referring now more particularly to Figs. 2 to 5, the bifurcated inner end of the slide g^x has fixed therein a transverse pivot-pin 15 for the auxiliary filling-detector, the latter comprising a head g^8 , having ears g^4 to rock on the pin and provided with tines g^5 and a body g^6 , having a loop-like tail g^7 and ears g^8 , pivotally mounted on the pin 15. A spring 25 is coiled around the said pin, and the ends of the spring bear, respectively, on the body g^6 and the tine-head g^8 , the winding of the spring being such that normally 105 the head g^8 is held against the beveled ends 30, Figs. 4 and 5, of the ears g^8 on the body. Normally, therefore, the body and tines are maintained in the relative position clearly shown in Fig. 5, and they will rock or tilt as 110 a whole on the pin 15 when the filling engages the tines on every alternate beat-up of the lay, and if on such a detecting-pick the filling is absent the tail g^7 will be engaged by the hook w^x of the weft-hammer W^x , and the 115 slide g^x will be moved outward in usual nanner. The head g^8 has secured to one of its ears g^4 a depending lug g^9 , Figs. 2 and 3, and secured to the stand g^2 is a finger g^{10} , provided with an inturned end g^{12} , extending 120 into the path of the lug g^9 , when the slide g^x is moved outward, the said finger being so located as to permit tilting of the filling-detector when the filling is present, as shown in dotted lines, Fig. 2, and so long as the loom is running properly the tilting will be effected on every alternate pick. If the filling fails, however, the detector will not be tilted on the detecting pick and the normal or full-line position of the detector, Fig. 2, will be undis- 130 turbed, so that the weft-hammer W^x will move the slide outward, and as soon as the lug g^9 meets the end g^{12} of the finger g^{10} the head g^8 and tines of the detector will be swung on the

fulcrum 15 relatively to the body g^8 and its tail into the position shown in Fig. 3 by the time the slide is in its extreme outward position, the spring 25 permitting the relative movement of the parts of the detector. Then the tines g^5 will be above the path of the filling, and the filling laid on the shot of the shuttle immediately succeeding replenishing will be in a plane or path below and out of the range of such tines. It will be remembered that this filling laid on the first shot extends from the feeder of the replenishing mechanism to the cloth and is termed the "filling" end, and it remains until severed by devices designed therefor; but by my present invention it cannot interfere with the co-operation of the auxiliary filling-detector and the running filling laid on picks succeeding that on which the filling end is laid. Assuming that the position of the filling end is indicated at t^x , Fig. 3, and that it has just been laid, the corresponding position of the slide g^x and tines g^5 of the auxiliary filling-detector is shown in Fig. 3, the slide being just about to return to normal position, and as the slide moves inward the tines g^5 will descend, but behind the filling end t^x and between it and the running filling which will be laid on the second pick after replenishing. Consequently the auxiliary detector will respond only to the presence of the running filling, and it will be entirely irresponsible to the filling end t^x , the detector having been lifted over and brought down behind it. In other words, said filling end has been jumped by the auxiliary filling-detector, and so far as the latter is concerned it is immaterial when the filling end is severed.

The position of the filling end, fork-tines g^5 , and running filling is fairly indicated in Fig. 2, wherein the tines in full lines are shown behind the filling end t^x and in front of the running filling t , laid on the second pick following replenishing.

It will be evident from an inspection of Fig. 1 that the main filling-detector detects only on the picks when the shuttle travels from right to left and the auxiliary detector on the intermediate picks, and, further, that it is the running filling which always co-operates with either detector and never the filling end.

Inasmuch as the latter portion of filling extends only to the edge of the cloth the continuation of the filling on the same pick becomes the running filling at the other side of the loom to co-operate with the main filling-detector.

The weft-hammers W W^x have opposite movements, being timed to co-operate with their respective filling-detectors upon detection by the latter of filling failure, and as the auxiliary detector-slide will always be moved outward on the pick immediately before the first shot of fresh filling the auxiliary detector will always be rendered irresponsible to the action of the filling end, as has been described.

I have shown herein one practical embodi-

ment of my invention without attempting to show or describe the various changes or modifications thereof which may be made by those skilled in the art without departing from the spirit and scope of my invention, which, so far as I am aware, is broadly new.

Having fully described my invention, what I claim as new, and desire to secure by Letters Patent, is—

1. In a loom, filling-replenishing mechanism, two filling-detectors, take-up mechanism controlled by both detectors to arrest its operation upon detection of filling failure by either detector, one of said detectors controlling the operation of the replenishing mechanism, and means to render the other detector irresponsible to the presence of the filling end due to filling replenishing.

2. In a loom, filling-replenishing mechanism, two filling-detectors located at opposite sides of the loom, take-up mechanism controlled by said detectors to arrest its operation upon detection of filling failure by either detector, one of said detectors controlling the operation of the replenishing mechanism, and means to render the other detector, located at the replenishing side of the loom, irresponsible to the presence of the filling end due to filling replenishing.

3. In a loom, filling-replenishing mechanism, two filling-detectors, take-up mechanism controlled by both detectors to arrest its operation upon detection of filling failure by either detector, one of said detectors controlling the operation of the replenishing mechanism, and means operative by or through failure of the filling to render the other detector irresponsible to the presence of the filling end due to the operation of the replenishing mechanism.

4. In a loom provided with mechanism operative automatically upon filling failure to provide a fresh supply of filling, a filling-detector located at the same side of the loom, take-up mechanism controlled by said detector to arrest its operation upon detection of filling failure by the detector, and means to prevent operative engagement of said detector with an intact filling end between the cloth and the replenishing mechanism resulting from the operation of the latter.

5. In a loom provided with mechanism operative automatically upon filling failure to provide a fresh supply of filling, a filling-detector located at the same side of the loom, take-up mechanism controlled by said detector to arrest its operation upon detection of filling failure by the detector, and means to move said detector into position behind the filling end presented by the operation of the replenishing mechanism, to co-operate only with the running filling.

6. In a loom provided with mechanism operative automatically upon filling failure to provide a fresh supply of filling, a filling-detector located at the same side of the loom, take-up mechanism controlled by said de-

5 tector to arrest its operation upon detection of filling failure by the detector, and means to move said detector over, and into operative position behind, the filling end presented by the operation of the replenishing mechanism, to thereby render said detector responsive to the running filling and irresponsible to the filling end.

7. In a loom, filling-replenishing mechanism, two filling-detectors, take-up mechanism controlled by both detectors to arrest its operation upon detection of filling failure by either detector, one of said detectors controlling the operation of the replenishing mechanism, and means operative upon failure of filling to lift the other detector above, and move it over and behind, the filling end presented by the operation of the replenishing mechanism, into position to coöperate only with the running filling.

8. In a loom, filling-replenishing mechanism, take-up mechanism, two filling-detectors located at opposite sides of the loom, connections between one detector and the replenishing and take-up mechanisms, connections between the other detector and the take-up mechanism only, and means operative upon detection of filling failure by the latter detector to operatively position it behind the filling end due to filling replenishing, whereby said detector is rendered irresponsible to the filling end and responsive to the running filling.

9. In a loom, stopping means, filling-replenishing mechanism, means, including a main filling-detector, to effect the operation of said mechanism upon detection of filling failure, and to operate the stopping means after a predetermined number of successive operations of said mechanism, an auxiliary filling-detector, take-up mechanism, independent connections between it and said detectors, to arrest operation of the former upon detection of filling failure by either detector, and means to move the auxiliary detector into operative position in front of the running filling, but behind the filling end due to the operation of the replenishing mechanism.

10. In a loom, filling-replenishing mechanism, main and auxiliary filling-detectors, the former controlling the operation of said mechanism, take-up mechanism controlled by both detectors to arrest its operation upon detection of filling failure by either, the auxiliary detector comprising a tail and tines yieldingly connected therewith, and means to effect relative movement of said parts upon the normal operation of the detector due to filling failure, to thereby lift the tines above the filling end due to filling replenishing, the return of the detector as a whole to detecting position causing the tines to descend behind such filling end in readiness to coöperate with the running filling.

65 11. In a loom, filling-replenishing mechanism, a main filling-detector, controlling the operation of said mechanism, an auxiliary de-

70 tector at the replenishing side of the loom, including tines movable with and also relatively to the body of the detector, a detector-slide, means to move it when filling failure is detected by the detector, means to lift the tines upon such slide movement, to permit passage thereunder of the filling end due to filling replenishing, return of the slide permitting descent of the tines to normal position but behind the filling end, and take-up mechanism the operation of which is arrested by or through the auxiliary detector upon detection thereof of filling failure.

75 12. In a loom, filling-replenishing mechanism, a main filling-fork controlling the operation of said mechanism, an auxiliary filling-fork located at the replenishing side of the loom and comprising a pivotally-mounted, 80 loop-like body, tines, and a yielding connection therebetween, a fork-slide, means to move it when the fork detects filling failure, a fixed device to lift the tines relatively to the body upon such slide movement, and take-up mechanism the operation of which is arrested by or through the auxiliary fork upon detection of filling failure, the return of the said fork-slide permitting the tines of the auxiliary fork to return to operative position in 95 front of the running filling but behind the filling end due to filling replenishing.

13. In a loom provided with filling-replenishing mechanism, main and auxiliary filling-forks located at opposite sides of the loom, 100 the former controlling the operation of said mechanism, take-up mechanism the operation whereof is arrested by or through either filling-fork upon detection of filling failure, and means to automatically, and temporarily lift 105 the tines of the auxiliary fork upon failure of the filling in front of the latter, whereby, upon subsequent return of the tines to normal position they will be behind the filling end due to the operation of the replenishing mechanism, and irresponsible to the action of such filling end.

14. In a loom, filling-replenishing mechanism at one side thereof, main and auxiliary filling-detectors, located at opposite 115 sides of the loom and each including a pivotally-mounted fork, a supporting-slide, and an actuator to move the slide upon detection of filling failure by its fork, the forks detecting upon alternate picks, the replenishing mechanism being controlled by the main detecting device, take-up mechanism the operation whereof is arrested upon detection of filling failure by either detecting device, and means, operative upon movement of the auxiliary 120 slide by its actuator, to lift the auxiliary fork above the path of the filling at the replenishing side of the loom, return of the auxiliary slide to normal position after filling replenishing permitting the auxiliary fork to resume 125 its operative position in front of the fresh running filling but behind the filling laid on the pick immediately following filling replenishing.

15. In a loom, filling-replenishing mechanism, main and auxiliary filling-detectors, the former being located at the side of the loom opposite said mechanism and controlling its 5 operation and the auxiliary detector at the replenishing side of the loom, take-up mechanism the operation whereof is arrested upon detection of filling failure by the auxiliary detector, and means to operatively position 10 the auxiliary detector behind the filling laid on the pick immediately following filling replenishing and in front of the path of the running filling laid on the next pick.
16. In a loom, filling-replenishing mechanism, main and auxiliary filling-detectors, the former being located at the side of the loom opposite said mechanism and controlling its 15 operation and the auxiliary detector at the replenishing side of the loom, take-up mechanism the operation whereof is arrested upon 20 detection of filling failure by the auxiliary detector, and means to lift the auxiliary de-
- tector over, and restore it to position behind, the filling laid on the pick immediately following filling replenishing and in condition 25 to detect presence or absence of the running filling laid on the next and alternate picks.
17. In a loom, filling-replenishing mechanism, means to control the time of operation thereof, a filling-detector located at the 30 replenishing side of the loom, to detect filling failure, take-up mechanism the operation whereof is arrested by or through said detector upon filling failure, and means to render said detector irresponsive to the filling 35 laid on the first pick following replenishing.

In testimony whereof I have signed my name to this specification in the presence of two subscribing witnesses.

CHARLES F. ROPER.
